(57) **CLAIM**

The ornamental design for a respirator mask as shown and described.

DESCRIPTION

FIG. 1 is a top perspective view of a respirator mask, according to the present design.

FIG. 2 is a front elevation view of the respirator mask of FIG. 1.

FIG. 3 is a rear elevation view of the respirator mask of FIG. 1.

FIG. 4 is a right-side elevation view of the respirator mask of FIG. 1.

FIG. 5 is a left-side elevation view of the respirator mask of FIG. 1.

FIG. 6 is a top plan view of the respirator mask of FIG. 1; and,

FIG. 7 is a bottom plan view of the respirator mask of FIG. 1.

The broken lines shown in the drawings depict portions of the respirator mask that form no part of the claimed design.
